UNITED STATES PATENT OFFICE.

CHARLES T. MASON, OF SUMTER, SOUTH CAROLINA, ASSIGNOR, BY DIRECT AND MESNE ASSIGNMENTS, TO THE AMERICAN WALTHAM WATCH COMPANY, OF MASSACHUSETTS.

ANTI-MAGNETIC WATCH.

SPECIFICATION forming part of Letters Patent No. 406,364, dated July 2, 1889.

Application filed June 26, 1888. Serial No. 278,256. (No model.)

To all whom it may concern:

Be it known that I, CHARLES T. MASON, of Sumter, in the county of Sumter and State of South Carolina, have invented a new and Improved Magnetic Shield for Watch-Balances, of which the following is a specification, reference being had to the annexed drawings, forming a part thereof, in which—

Figure 1 is a plan view of a watch-movement to which my improvement has been applied, and Fig. 2 is a transverse section taken on line *x x* in Fig. 1.

Similar letters of reference indicate corresponding parts in both views.

The object of my invention is to provide a simple and effective device for protecting the balances of watches from magnetism.

My invention consists in an annular case surrounding the balance-wheel a short distance from its periphery and permanently secured to the lower watch-plate.

The watch-movement *A* is of the usual description, having the balance *B* formed of brass and steel and provided with the hair-spring *a*. Around the periphery of the balance-wheel is placed a ring *C*, of soft iron, provided with an inwardly-projecting flange or fillet *b*, which is secured to the bottom plate of the watch by screws *c*, as shown in Fig. 1.

It is well known that a magnetic body surrounded or inclosed by a body of soft iron is shielded from external magnetic influences. I have made use of this principle in my im-

proved shield for watch-balances by surrounding the balance with soft iron, thereby preventing the steel of the watch-balance from being magnetized by induction from the external magnets.

My improved device can be applied to and form a part of a new watch, or it may be readily adapted to watches already in use.

If the mainspring or other steel part of a watch provided with my improved shield be magnetized, it will have no effect upon the operation of the watch, as the magnetism, which would without the shield act upon the balance, will be absorbed by the ring *C*.

Having thus described my invention, I claim as new and desire to secure by Letters Patent—

1. The combination, with a watch-balance, of a ring of magnetic metal encircling or surrounding the said watch-balance, substantially as described.

2. The combination, with the balance-wheel of a watch, of a soft-iron ring surrounding the balance-wheel, substantially as specified.

3. The combination, with a balance-wheel of a watch, of a ring of soft iron surrounding the balance-wheel and provided with an inwardly-projecting flange on its lower part, substantially as herein shown and described.

CHARLES T. MASON.
